UNITED STATES PATENT OFFICE.

ADOLPH E. MEYER, OF WEBSTER GROVES, MISSOURI, ASSIGNOR TO TEXTILE PRODUCTS MANUFACTURING COMPANY, OF ST. LOUIS, MISSOURI, A CORPORATION OF MISSOURI.

COTTON-PICKER'S SACK.

Application filed December 1, 1919. Serial No. 341,762.

To all whom it may concern:

Be it known that I, ADOLPH E. MEYER, a citizen of the United States of America, a resident of Webster Groves, in the county of St. Louis, State of Missouri, have invented certain new and useful Improvements in Cotton-Pickers' Sacks, of which the following is a full, clear, and exact description, reference being had to the accompanying drawings, forming a part of this specification.

My invention relates to a sack for use by cotton pickers in gathering cotton in the field, the invention having for its object to produce a cotton picker's sack of very simple and inexpensive nature with the mouth of the sack so formed as to permit easy access to the sack. The sack is preferably so formed as to permit a reversal of the sack at any time, so that the wear incident to dragging the sack on the ground may not be imposed upon one side of the sack alone, but on both sides of it, to lengthen its serviceability.

Fig. I is an elevation of my cotton picker's sack.

Fig. II is a vertical section.

Fig. III is an enlarged horizontal section taken on line III—III, Fig. I.

Fig. IV is an enlarged horizontal section taken on line IV—IV, Fig. I.

Fig. V is an elevation of a modified form.

A designates the body of my cotton picker's sack terminating in an open upper end.

The sack body A has permanently secured to it at its edges extension straps 1, which project above the mouth of the sack and receive the attachment of a shoulder strap 2, by which the sack may be supported on the shoulder of the cotton picker in carrying it or dragging it upon the ground.

My cotton picker's sack is constructed particularly with the object in view of using it with either wall of the sack body at the front and either wall at the back, with means provided at the mouth of the sack, which may be secured to either wall and occupy a position above the back wall as an extension higher than the front wall. This facilitates the introduction of the cotton picker's hand into the sack, inasmuch as the front wall, over which the hand is passed in introducing the cotton, is lower than the rear wall at the mouth of the sack.

To accomplish the desired above stated result, I provide an adjustable top flap or

top wall member 3, which is secured to the edge portions of the sack, preferably to the extension straps 1 at the edges of the sack and which is attachable to either wall of the sack body. Suitable fastening means 5, carried by the walls of the sack body at their upper edges and the adjustable top wall member 3, are adapted to be engaged with each other to connect said top wall member 3 to either wall of the sack, according to which of the sack walls is to serve as the back wall in the use of the cotton picker's sack.

It will be apparent that when the adjustable top wall member 3 is secured to a main wall of the sack, said top wall member projects higher than the other wall of the sack body, and as a consequence of such projection handfuls of cotton may be readily introduced through the open mouth of the sack over the upper edge of the front wall of the sack, which is of less height than the wall extension serving as a barrier against which the cotton picker's hand strikes to prevent the movement of the hand across the mouth of the sack.

The two main walls of the sack form a single compartment and the extension wall member 3 lies between these main walls to provide two mouths for the single compartment. This wall member 3 is movable from one main wall to the other so as to open one mouth and close the other.

In the modified form shown in Fig. V, the sack body A' has secured to its side edges strap extensions 1^a, and the extension wall member 3^a is permanently secured to the sack body but is separated from the strap extensions. The side edges of the extension wall member are connected with the shoulder straps by any suitable connecting means, such, for example, as hooks 6 which may engage rings at the ends of the shoulder strap.

I claim:

1. A cotton picker's sack comprising a body portion having two main walls, and a top extension wall member permanently secured at its ends to said body portion adjacent the side edges of the latter, said top extension wall member being attachable to and detachable from the upper ends of both of said main walls.

2. A cotton picker's sack comprising two main walls with a single compartment between them, and a top extension wall mem-

ber having its lower margin interposed between said main walls to provide two mouths for said single compartment, the upper margin of said top extension wall member being 5 above said main walls, and said interposed lower margin being movable from one of said main walls to the other so as to open one mouth and close the other.

3. A cotton picker's sack comprising a 10 body having two main walls, and a top extension wall member having its ends permanently secured to the sack body, the intermediate portion of said extension member being attachable to and detachable from 15 both of the main walls.

4. A cotton picker's sack comprising a body having two main walls, extension straps secured to the side edges of the sack body, and a top extension wall member secured 20 to said extension straps, said extension wall member being extended into the sack

and attachable to both of said main walls.

5. A cotton picker's sack comprising a body having two main walls, side straps secured to the side edges of said body, a top extension wall member secured to said side straps, a shoulder strap connected to said side straps, the lower portion of said top extension wall member being entirely within the sack, and detachable fastening means 30 whereby said lower portion may be selectively attached to either of said main walls.

6. A cotton picker's sack comprising a body portion having two main walls, and a top extension wall member permanently secured at its ends to said body portion adjacent the edges of the latter and means for attaching the top extension wall member to either of the main walls.

In testimony that I claim the foregoing 40 I hereunto affix my signature.

ADOLPH E. MEYER.
